UNITED STATES PATENT OFFICE.

FRANK T. VAN WOERT, OF NEW YORK, N. Y.

ARTIFICIAL TOOTH.

1,142,385.

Specification of Letters Patent.

Patented June 8, 1915.

Application filed April 16, 1913. Serial No. 761,520.

To all whom it may concern:

Be it known that I, FRANK T. VAN WOERT, a citizen of the United States, residing in the borough of Brooklyn, county of Kings, city and State of New York, have invented certain new and useful Improvements in Artificial Teeth, of which the following is a specification.

This invention relates to artificial teeth, 10 and aims to provide certain improvements therein.

The invention is particularly directed to a method of forming a connection between the attaching pins or posts by means of 15 which the tooth is connected to the plate.

According to the present invention I provide a construction in which the fastening pins are securely locked in place by mechanical means after the tooth is baked. I 20 also prefer to so construct the parts that spaces are left between the pins and surrounding tooth walls, so that when the teeth are applied to the plate the rubber composition is capable of being forced practically 25 completely around the pins, so that the joint between the pins and tooth is adequately cushioned whereby the danger of fracture is reduced or avoided.

Referring to the drawings, illustrating my 30 invention, Figure 1 is an inner side view of a tooth provided by my invention, the pins being shown in section as indicated by the line 1—1 in Fig. 3. Fig. 2 is a sectional view of Fig. 3, taken on the line 2—2, the 35 pin member being omitted. Fig. 3 is a sectional view taken on the line 3—3 in Fig. 1. Fig. 4 is a perspective view of the inner face of the tooth. Fig. 5 is a sectional view of the tooth of Fig. 1, shown applied to the 40 plate.

Referring to the drawings, let A indicate an artificial tooth usually formed of porcelain and B the fastening means as a whole. According to the present invention I form a 45 socket or chamber in the tooth by the aid of a suitable core which is inserted in the porcelain when the tooth is molded. Such core is best formed of material which will burn out during the process of baking the 50 tooth. The exact form of chamber depends upon the construction of pin or post which is to be used.

The fastener herein illustrated comprises a body portion H consisting of a yieldable 55 and preferably elastic bar uniting the pins J J. The ends of the bar H are shown pro-

jecting at I I beyond the points of its junction with the pins. The pins are shown provided with transversely disposed ends or heads j j directed outwardly and each paralleling the bar end I at that side of the fastener. The socket or chamber has a seat for the bar which in the illustration comprises a portion E for the inter-pin portion H of the bar and portions F F for the bar ends 60 I I. A slot or passage-way comprising two portions leads from the exterior of the tooth to the bar seat. One of these portions E' is located on the plane of the seat E and has one side opening into said seat and its 65 opposite side curved outwardly therefrom. The other portion C of the slot is disposed transversely of the bar seat and is curved and has one side registering with the curved 70 side of the slotted portion E'. The ends c c 75 of the curved portion of the slot are disposed on a line with the ends F F and inwardly thereof. There is a solid portion D over-hanging the seat E and a portion of the slot E' and portions G G over-hanging 80 the ends F F of the seat. The fastener preferably is a one piece structure.

The chamber and fastener are of such relative proportions that when the bar is in its normal condition and seated, its inter-pin portion H will be disposed in the seat portion E, its ends I I in the seat ends F F and the pins J J in the ends c c of the slot C. When in this position it will be securely 85 locked in place, the relative proportions of the seat or socket and the portion of the fastener which is in it being such that the parts 90 cannot be disassembled without dislocation or breakage.

To insert the fastener in the chamber and seat the same the bar H is flexed sufficiently to traverse the slot portion C and is then caused or permitted, as the case may be, depending upon the condition of elasticity 95 of the bar, to assume its normal condition and shape and traverse the slot portion E' and the bar and its ends enter the seat.

It will be seen that in effect the construction provided is such that when the pin member is introduced it is locked in place, and this locking action is such that the pin 100 cannot be removed by any working strain that may be applied to it, after it is once inserted. In the construction illustrated the bar may be formed of resilient material 105 so that it may be given a sufficient bow or bend to pass it within the exterior opening 110

C, the bar expanding when it reaches the bottom of the socket and automatically assuming the position of Fig. 1, or the bar may be made of material which is sufficiently pliable to permit of its being bent sufficiently to be introduced through the opening and afterward straightened by the use of a suitable tool or the like. According to either method the exterior opening in the tooth is shaped to permit the introduction of the pin when the latter is distorted, and the interior opening seat is shaped to securely lock the bar when the latter assumes substantially its normal condition, that is not flexed. It is to be noted that in this structure the socket and the fastener are of such relative dimensions and formations that the portion of the fastener seated in the socket is bent during such seating and that the last stage of the seating movement of such portion is transverse to the working strain applied to the fastener through the pins. The fastener when seated is in the form of a loop located under a shelf integral with the tooth. The engaging face of the shelf is shown disposed transversely of the working strain upon the fastening pins. After the fastener has been seated the bending incident to the working strain cannot remove the fastener from its seat.

An important feature of the construction just described is that while the fastener is securely locked so that it is practically impossible to remove it without breaking the tooth, nevertheless the construction permits the provision of spaces around the fastener into which the rubber composition may flow so that it practically surrounds the metal at all points, and provides a cushion between the metal and porcelain which tends to prevent fracture of the porcelain when the tooth is in use. In Fig. 5 I have illustrated a tooth connected to a plate which illustrates this feature, the rubber being indicated by the reference letter K.

The relation between the pin ends or heads *j* and the bar ends *I* is such that the strain holding the tooth in position is placed upon the bar and its ends in such direction that it withstands the strain without distortion. The tooth at this point presents over-hanging portions *G* for engaging the ends *I*, which ends coöperate with the over-hanging portion *B*.

In the invention as thus described when the tooth is applied to the rubber plate, the rubber, as before stated, enters into the recesses and not only forms a cushion, but also fills all of the spaces left free and effectually prevents any dislodgement or movement of the pin member, thus securing a firm and rigid connection between the plate and the tooth.

It will be observed that by my invention

I provide an artificial tooth which can be very easily and cheaply manufactured without the use of expensive metals or delicate operations. Further that the pin members are strongly and firmly connected to the tooth so as to be practically inseparable therefrom when once inserted; also that after the tooth is applied to the plate it is provided with an adequate cushion or packing so that liability of breakage is minimized.

It will be understood that the form of the invention shown and described is illustrative and that I do not wish to be limited thereto, as various changes can be made therein within the scope of the claims without departing from the spirit of the invention.

What I claim is:—

1. An artificial tooth having an elongated seat *E* formed with extensions *F* *F*, an opening *C* leading to said seat, and said tooth having over-hanging portions *D* and *G* *G*, in combination with a pin member having a body portion *H* and extensions *I* *I*, said body portion and extensions being adapted when the pin member is temporarily distorted to pass through said opening *C* and when restored to normal conditions to lie within said seat, the body of said pin member lying beneath said over-hanging portion and said extensions *I* *I* lying beneath said over-hanging portions *G* *G*.

2. As an article of manufacture a tooth having within it a fastener seat and being provided with a slot having a portion disposed in the plane of the seat and opening into the same at one side and at the other side being curved outwardly, and another portion disposed transversely of the seat and curved to register with the curved side of the first-mentioned portion.

3. The combination with a tooth having a chamber and a curved slot leading thereto equal in length to the length of the chamber and having its ends located in front of the chamber, of a yieldable bar capable of traversing the slot when flexed and of occupying the seat when in normal position, and pins carried by such bar inwardly of its ends and located in position to occupy the ends of the slot when the bar is seated.

4. The combination with a fastener comprising a flexible bar and a pair of pins carried by the bar inwardly of its ends, and a tooth having an undercut seat for such bar, the bar being located in the seat and unflexed.

5. The combination with a tooth having within it a fastener seat and being provided with a slot having a portion disposed in the plane of the seat and opening into the same at one side, and another portion being curved and disposed transversely of the seat

of the first-mentioned portion, of a yieldable bar capable of traversing the slot when flexed and of occupying the seat when in normal position, and pins carried by such bar and located in the slot when the bar is seated.

6. The combination with a tooth having within it a fastener seat, of a fastener in the form of a pair of pins connected by a loop, said loop being disposed in the seat, the tooth being provided with an integral

shelf free at its ends and one side, and having a face engaging the loop and disposed transversely of the working strain upon the pins.

15

In witness whereof, I have hereunto signed my name in the presence of two subscribing witnesses.

FRANK T. VAN WOERT.
